UNITED STATES PATENT OFFICE.

WALTER C. REED, OF BURNHAM, ILLINOIS.

TOOL FOR REMOVING HANHOLE PLATES.

1,410,597.

Specification of Letters Patent. Patented Mar. 28, 1922.

Application filed August 18, 1920. Serial No. 404,440.

To all whom it may concern:

Be it known that I, WALTER C. REED, a citizen of the United States, residing at Burnham, in the county of Cook and State of Illinois, have invented certain new and useful Improvements in Tools for Removing Handhole Plates, of which the following is a specification, reference being had to the accompanying drawings.

10 This invention relates to devices for removing the hand hole plate from boilers, and particularly from fire tube locomotive crane boilers.

When boilers of this character are taken from service to be washed out, it is necessary that the hand hole plates be removed, and this is usually done by hand. Often when taking plates out by hand, they slip off the fingers and fall down into the boiler, and 20 this necessitates hours of delay in cooling the boiler off and fishing around to get a hold on the hand hole plate. If the plate should fall behind a staybolt, it is almost impossible to remove it, and if, on the other 25 hand, it is allowed to remain and happens to have fallen alongside of the fire sheet, a hole will be burned in the fire sheet at this point because the hand hole plate prevents the water from coming in close contact with 30 the sheet to cool it.

The general object of my invention is to provide a very simple and effective tool for removing these hand hole plates.

And a further object is to provide a tool 35 of this character which may be readily engaged with the plate and from which the plate will not become detached within the boiler even by a violent shaking:

A further object is to provide a hand 40 hole plate removing tool having a hand hole engaging tongue or member pivotally connected to the extremity of the shank or handle which is adapted to be inserted in the socket commonly found on this type of hand 45 hole plates, and which will permit the hand hole plate to be carried into the boiler and then which will permit the hand hole plate to fall into a horizontal position whereby it may be removed from the hand hole and 50 which is so constructed as to prevent the hand hole plate from falling in any other direction.

Other objects will appear in the course of the following description.

My invention is illustrated in the accompanying drawings, wherein:

Figure 1 is a side elevation partly in section of a hand hole plate removing tool constructed in accordance with my invention;

Figure 2 is a front elevation of the tool;

Figure 3 is a sectional view through a boiler and hand hole plate showing how the tool is applied;

Figure 4 is a like view to Figure 3, but showing the hand hole plate in the act of being removed.

Referring to these drawings, 10 designates the handle or shank of my improved implement, which is circular in transverse section and longitudinally curved. One end 70 of this shank is angularly bent, as at 11, and this end of the shank at its extremities is widened, as at 12, and formed with a kerf 13 defining two ears on each side of the kerf. The bottom 14 of this kerf is inclined and 75 lies approximately at right angles to that portion of the handle or shank immediately opposite these ears. The opposite end of the handle or shank is bent to form an eye 15 or may be formed in any suitable manner. 80

Pivoted to the bifurcated end of the shank is a tongue 16 which is approximately rectangular in form and relatively thick, and which is formed with the projecting ear 17 adapted to be received in the slot 13 and be 85 pivoted to the portion 12 of the shank by means of a transverse pivot bolt, rivet or pin 18. This ear 17 at its outer end has one corner rounded off, as at 19, while between this rounded portion and the outer 90 face of the ear, that is the face away from the handle, the edge face of the ear 17 is flattened, as at 20. The rounded corner 19 has a radius equal to the shortest distance between the flat face 14 of the bottom of 95 the kerf 13 and the axis on which the ear turns, but the distance between the pivot pin 18 and the extremity of the flattened face 20 of the ear remote from the pivot pin 18 is greater than this radius so that 100 the ear has only a limited movement of oscillation from the position shown in Figure 1 to the position shown in Figure 4. When it is in the position shown in Figure 1, the flat face 20 comes in contact with the bottom 14 of the kerf 13, but the ear is held in the position shown, which is its position 105 when entering the socket in the hand hole

plate. The hand hole plate is designated *A* and is of conventional form, and upon its face is provided with a U-shaped socket, designated generally *B*, which overhangs the plate, this socket being cut away at its middle, as at *b*. This hand hole plate, when in place, has its socket extending horizontally.

In the use of this device, the handle is disposed as illustrated in Figure 3, with the tongue in a horizontal position, and then the tongue is inserted in the socket in the plate until it engages fully with the overhanging wall of the socket and the reduced portion 11 of the shank or handle is disposed to extend 15 through the cut away portion *b* of the socket. It will be understood, of course, that the tool is inserted into the T-shaped slot and the hand hole plate pushed into the boiler. The tool is then given a quarter turn with 20 the hand hole plate so that the tongue of the tool faces upward. In this position, the hand hole plate cannot fall backward into the boiler on account of the stop formed by the face 20 coming in contact with the bottom of the kerf 13, but this tongue can fall 25 outward, that is toward the handle, if the tool be tilted forward slightly, and carries with it the hand hole plate so that the hand hole plate is in the position shown in Figure 30 4, permitting the tool and the hand hole plate to be readily removed from the boiler.

It will be seen that the hand hole plate cannot fall inward, and that after it has been moved to a horizontal position, it can 35 fall no further because it rests against the shank itself. This implement will remove a hand hole plate with no danger of its falling into the boiler and will firmly engage the hand hole plate until the tool 40 has been deliberately detached from the hand hole plate.

I claim:—

1. A hand hole plate removing tool comprising a shank, one end of which is angularly extended and formed with a tongue

pivoted to the extremity of the angular portion for free movement in one direction, said tongue being adapted to be inserted in the socket of a hand hole plate.

2. A hand hole plate removing tool comprising a shank, one end of which is curved, and a tongue pivoted to the extremity of the curved end of the shank and formed to be inserted within the socket of a hand hole plate, the tongue and extremity of the shank being formed to provide a stop limiting the movement of the tongue away from the shank, the tongue having movement toward the shank.

3. An implement of the character described comprising a shank having one end angularly bent and formed to provide spaced ears, a tongue having a lug disposed between the spaced ears and pivoted thereto, the tongue being adapted to be inserted in the socket of a hand hole plate, the tongue and shank being formed to provide coacting stop surfaces permitting a limited movement of the tongue away from the shank but permitting the tongue to move toward the shank.

4. An implement of the character described comprising a shank, one end of which is angularly bent, the extremity of this angularly bent end being formed to provide two spaced ears separated by a kerf, the bottom of the kerf being flat and disposed at approximately a right angle to the shank, and a tongue rectangular in form, the tongue having at one side an outwardly projecting lug fitting between the ears and pivoted thereto, said lug having that corner adjacent the shank rounded and the outer corner formed with a flat face adapted to engage with the bottom of the kerf to limit the outward movement of the tongue away from the shank.

In testimony whereof I hereunto affix my signature.

WALTER C. REED.
